UNITED STATES PATENT OFFICE.

OLIVER CROSBY, OF ST. PAUL, MINNESOTA, ASSIGNOR TO AMERICAN HOIST & DERRICK CO., OF ST. PAUL, MINNESOTA, A PARTNERSHIP.

ROPE CLAMP.

1,271,284.

Specification of Letters Patent.

Patented July 2, 1918.

Application filed March 20, 1918. Serial No. 223,547.

To all whom it may concern:

Be it known that I, OLIVER CROSBY, a citizen of the United States, resident of St. Paul, county of Ramsey, State of Minnesota, have invented certain new and useful Improvements in Rope-Clamps, of which the following is a specification.

The object of my invention is to provide means coöperating with the block member 10 of the clamp or the part that is mounted on the threaded ends of the U-bolt for gripping the rope or cable to prevent it from slipping in the clamp under severe or unusual strain.

A further object is to provide a gripping member which will clamp the rope with an increasing pressure proportionate to the movement of the rope in the clamp. That is, the slipping of the rope will automatically result in increasing the pressure of the clamp thereon and continue to increase such pressure if the slippage continues.

A further object is to provide a comparatively simple, inexpensive adjunct to an ordinary type of rope clamp which will render it particularly effective for the purpose designed.

The invention consists generally in various constructions and combinations, all as hereinafter described and particularly pointed out in the claims.

In the accompanying drawings forming part of this specification,

Figure 1 is a sectional view of a rope clamp embodying my invention,

Fig. 2 is a side view of the clamp,

Fig. 3 is a sectional view taken on a line at right angles substantially to the section line of Fig. 1,

Fig. 4 is a perspective view of the rope gripping member between which and the U-bolt the rope or cable is clamped.

In the drawing, 2 represents a U-shaped bolt having threaded ends 3 for clamping nuts 4. 5 is a block having sockets 6 therein 45 wherein the threaded ends of the U-bolt are slidable. The block 5 has upwardly projecting brackets 7 formed thereon in pairs, with a recess 8 between them into which the ends of the rope or cable 9 to be clamped 50 together are placed, the U-bolt straddling the cable with its threaded ends projecting through the sockets in the block. In the bottom of the recess between the pairs of brackets 7 a seat 10 is formed, preferably

concave and adapted to receive a similar 55 shaped surface provided on the underside of a rocker member 11. This member is made flaring from the base toward the top and is provided with a concave upper surface 12, having ribs or corrugations 13 formed there- 60 in to fit the strands of the rope or cable against which it is seated, and the surface 12 is of sufficient area to have a broad bearing surface on the cable and the U-shaped portion of the bolt will be on the opposite 65 side of the cable and will be drawn against the cable surface when the nuts are tightened and the cable ends will be firmly clamped between the bolt and the surface of the member 11. This member 11 is free to 70 rock in its bearing on the block 10 when a strain is applied in either direction to the cable and as the center of the bearing surface 12 is a less distance from the axis of the rocking member than the end portions 75 of the surface 12, it follows that if the cable slips in the clamp and tilts the rocking member to one side or the other, the pressure of such member on the cable will immediately increase and continue to increase if the cable 80 continues to slip. The rocking member therefore has the function of a wedge for increasing the clamping effect of the U-bolt on the cable proportionately to the strain and slippage of the cable.

The rocking member may be made in various sizes, according to the purpose for which the clamp is to be used, and its shape may be modified and still be within the scope of my invention.

The upper portion of the rocking member projects between the bracket 7 and is guided thereby and while the member is free to rock lengthwise of the cable, it is held by the brackets against movement transversely 95 thereof.

The rocking member 11 may be prevented from falling out of place when the rope-cable is removed, by any suitable means, for instance by slightly bending or deflecting 100 inwardly the upwardly extending brackets 7 as indicated by dotted lines in Fig. 2, or by a stem 14, threaded into the bottom of the rocking member, and a cotter pin 15 as indicated in Fig. 3, but neither of such means 105 is absolutely necessary.

I claim as my invention:

1. A rope clamp comprising a U-shaped

5 bolt, a block slideable thereon, clamping nuts for the ends of said bolt, and a rocking member interposed between said block and the rope or cable to be clamped and having a bearing surface for such rope.

10 2. A rope clamp comprising a U-shaped bolt, a block slideable thereon, clamping nuts for said bolt and a member seated in said block and having a surface for contact with the cable to be clamped.

15 3. A rope clamp comprising a bolt to straddle the cable to be clamped, a block slideable on the ends of said bolt, clamping nuts for said ends, said block having brackets arranged in pairs with a recess between them to receive the cable ends to be clamped, and a member seated on said block and having freedom of oscillation therein and guided by said brackets, said member having a sur-

face between which and said bolt the cable is 20 clamped.

25 4. A rope clamp comprising a U-shaped bolt, a block slideable on the ends thereof, clamping nuts mounted on said bolt for engaging said block, said block having a concave seat formed in its inner face and a member having a correspondingly shaped surface to fit said seat and rock thereon and provided with a face between which and the curved portion of said bolt the cable is 30 clamped.

In witness whereof, I have hereunto set my hand.

OLIVER CROSBY.
